US00D849824S

(12) **United States Design Patent** (10) **Patent No.:** **US D849,824 S**
(45) **Date of Patent:** **** May 28, 2019**

(54) **SUNGLASSES**

(71) Applicant: **DaVinci II CSJ, LLC**, Fairfield, NJ (US)

(72) Inventor: **Damian Mucaro**, Hackensack, NJ (US)

(73) Assignee: **DaVinci II CSJ, Inc.**, Faurfield, NJ (US)

(**) Term: **15 Years**

(21) Appl. No.: **29/629,159**

(22) Filed: **Dec. 12, 2017**

(51) LOC (11) Cl. **16-06**

(52) U.S. Cl.

USPC **D16/314**

(58) **Field of Classification Search**

USPC D16/300, 313, 314, 321

CPC A61F 9/02; G02C 7/02

See application file for complete search history.
